UNITED STATES PATENT OFFICE.

JOHN BROUWERS, OF SPARTA, MICHIGAN.

FURNACE.

1,145,970.

Specification of Letters Patent. Patented July 13, 1915.

Application filed March 19, 1915. Serial No. 15,480.

To all whom it may concern:

Be it known that I, JOHN BROUWERS, a citizen of the United States of America, residing at Sparta, in the county of Kent, 5 and State of Michigan, have invented certain new and useful Improvements in Furnaces; and I do hereby declare the following to be a full, clear, and exact description of the invention, such as will enable others 10 skilled in the art to which it appertains to make and use the same.

This invention relates to furnaces, and it is an object and purpose thereof to provide new and improved constructions in furnaces 15 which permit the ready assembling of the furnace with a minimum of trouble and expense.

It is a further object of the invention to provide means dividing the chamber in 20 which air is heated in the furnace into a plurality of compartments from which heated air must escape through an associated furnace pipe leading to a room in the house heated by furnace, whereby the 25 pipes of shortest length in the furnace do not pass practically all of the heated air while the longer pipes pass but very little to the rooms with which they are connected.

Still further objects consist in the provision 30 of a furnace located horizontally and having a new and improved construction dividing the body thereof into a fire box with an ash pit below it, while the upper portion of the body is divided from the fire 35 box to produce a passageway to the chimney whereby all the products of combustion are brought into close contact with the air heating chamber so that the heat from said products may be given off, in a great measure 40 before reaching the outlet chimney.

Various other objects and purposes consisting of a pivotally mounted baffle wall for controlling the draft and in guard members keeping the fire in the furnace from the walls 45 of the body to prevent its burning out, will be apparent as understanding is had of the construction shown in the accompanying drawings, in which:

Figure 1 is a front elevation of the furnace. Fig. 2 is a vertical section taken transversely thereof. Fig. 3 is a vertical section taken longitudinally of the furnace. Fig. 4 is a front elevation of the grate with the 50 guard members applied thereto; and Fig. 5 is a plan view of the grate, the guard members being shown removed from one side of

said grate. Fig. 6 shows a view similar to Fig. 3 of the front part of a modified form of furnace construction.

Like reference characters refer to like 60 parts throughout the several views of the drawings.

In the construction of the furnace a cylindrical body is formed including a lower semi-cylindrical half 1 which, at its edges, 65 is turned outwardly to form horizontal flanges 2, and at its front and rear having integral flanges 3 and 4 projecting vertically therefrom. The body is completed by an upper semi-cylindrical half 5 which, at 70 its edges has outwardly extending flanges 6 adapted to seat on the flanges 2. Flanges 2 and 6 are connected together forming an open ended cylinder. The member 5 is further provided with the inwardly extending 75 horizontal flanges 7 opposite flanges 6 and at its front and rear edges with outwardly extending flanges 8 and 9 completing, with the flanges 3 and 4, heretofore described, bearing rings to which the front and rear 80 of the furnace may be secured.

The front of the furnace indicated at 10 is detachably attached to the body thus formed by means of bolts 11 through flanges 3 and 8 and in the same manner the back 12 85 is attached by bolts 13 to flanges 4 and 9. If desired the front and back may be extended laterally to each side and also above the cylindrical body to form a boundary for the chamber, said chamber being completed 90 by sides 14 connected by a top 15. In the top a plurality of furnace pipes 16 are secured serving as conduits to convey heated air from the air chamber to rooms of the house in which the furnace is installed. A 95 cold air inlet passage 17 may be entered into the air chamber in any convenient manner, the one shown in the drawing being merely for the purpose of illustration. It is of course apparent that the front and back 10 100 and 12 need not be extended to form the front and back of the air chamber but that the thin metal like that forming the top may be used to form the front and back of the air chamber while the front and back 10 and 12 need extend only to the edge of the flanges 3, 4, 11 and 13 as shown at 10^a in Fig. 6, this construction however, not changing any principle of operation.

Previous to the connection of the front 10 110 to the cylindrical body, a baffle 18 having a curved outline and provided with a back 19

formed as a segment of a circle is introduced into the body by sliding it inward on the flanges 7. Baffle 18 is secured to the front 10 by means of bolts 20 to hold it rigidly in place. When so positioned the back 19 is located a distance in front of the back 12 of the furnace and the top of the baffle is positioned a distance below the top of the cylindrical body previously described. A grate 21 of any approved construction is supported a distance above the bottom of the lower member 1 and at its rear end carries a baffle wall 22 hinged to a rod 23. An operating rod 24 is connected to the baffle wall and extends rearwardly through the back 12 and has a series of notches 25 cut therein on its underside which engage with the lower edge of the opening through the back. Rod 24 terminates in a handle 26 by means of which it may be manually operated to position the baffle wall in various positions with respect to the grate.

The back 12 has an opening therein normally closed by a door 27 at the upper portion of the body, while another door 28 closes an opening adjacent the lower portion of said cylindrical body. Similarly the front 10 has an opening therethrough normally closed by a door 29 directly above the member 18 and two doors 30 close openings in the front 10 which lead into the fire box formed by the grate 21 and the baffle 18. Below the grate 21 an opening is formed in the front 10 which is closed by the doors 31 through which access may be had to the ash pit located below the grate. Near its forward end the upper member 5 of the cylindrical body has an opening and a pipe 32 is connected to said member 5 in conjunction with this opening to carry away the products of combustion.

The air chamber formed between the cylindrical body and the outer inclosing members 14 and 15 is divided in its upper half by a plurality of vertical partitions 33 which on their lower edges are cut to fit closely against the upper half 5 of the cylindrical body and rest on the flanges 6 thereof, being formed at their outer edges to fit closely adjacent the inclosing members 14 and 15 of the air chamber. These partitions are positioned between the furnace pipes 16 and divide the upper half of the air chamber into a plurality of compartments from which any escape of air must be through its associated pipe 16 as will be readily understood. Instead of pipes 16 extending vertically from the air chamber at the central portion thereof as shown in full lines it may be desirable to have a larger number of pipes, especially with larger sizes of furnaces, and these may be positioned at an angle to the top 15 as shown in dotted outline at 34 in Fig. 1 and each of the compartments between partitions 33 may be further

divided by a vertical partition wall 35 so that each pipe 34 will have connection with a single compartment.

It is desirable that the fuel in the furnace shall not come in contact with the walls of the cylindrical body and to this end I have formed at each side of the grate 21 horizontal bars 36 in which a plurality of openings 37 are made adapted to receive vertical guards 38 which at their lower ends are detachably seated in the openings. These guards form a substantial barrier between the fire and the sides of the body preventing the fire from contacting with and burning through the body as would otherwise occur, while any guard 38 that becomes burned so as to be useless may be removed at will and a new one used in its stead.

With a furnace thus constructed it will be apparent that products of combustion are carried over the baffle wall 23 and under the back 19, passing between it and the back 12 of the furnace and thence forward between the baffle 18 and the top of the cylindrical body to the chimney 32. The products of combustion thereupon come in contact with the upper portion of the cylindrical body practically its entire length and heat given off therefrom will heat the air in the air chamber of which the upper portion of the body forms one boundary. The heated air passes out through the furnace pipes 16 or 24 and it is impossible for the air in one compartment to escape except through its associated furnace pipe. This construction is very easily made and quickly assembled. The upper and lower members 1 and 5 of the cylindrical body are readily cast as is also the front and back and the baffle 18 together with the grate and the guarding members 36 and 38 associated therewith. The assembling of the baffle 18 in the furnace is especially simple and effective. There are no parts outside of the grate and guards 28 that are liable to become useless and these may be readily replaced at any time. The baffle wall 22, by reason of its adjustable relation to the grate, may be swung to vary the passage of the products of combustion from the fire box over said wall and adjusted to conform to the particular circumstances under which the furnace may be used, while the location of the doors 27, 28 and 29 permit a very ready cleaning of the furnace at any time with little or no attendant trouble.

Various minor changes in construction may be resorted to without departing from my invention which is defined in the appended claims and comprises all modifications falling within the scope of said claims.

I claim:

1. In a furnace, a hollow body comprised of upper and lower halves each having outwardly extending horizontal flanges at its

- edges for securing the halves together and one half being provided with inwardly extending flanges, a curved baffle having a vertical back and resting on the inwardly extending flanges, said baffle being spaced from the upper half of the body and the back located a distance in front of the rear end of the body, front and back closures for the body, means surrounding the body 5 forming an air chamber between it and the body, a plurality of furnace pipes leading from the air chamber, partitions dividing the upper part of the air chamber into a plurality of compartments, one for each furnace pipe, a grate located in the lower half of the body, a baffle wall pivotally mounted at the rear end of the grate and means to adjust and hold the baffle wall in a plurality of positions with respect to the grate.
2. In a furnace, a hollow body comprised of upper and lower halves each having outwardly extending horizontal flanges at its edges for securing the said halves together, and one half being provided with inwardly extending horizontal flanges, a curved baffle having a vertical back and resting on the last named flanges, said baffle being spaced from the upper half of the body and the back located a distance in front of the rear end of the body, a front and a back closure to the body, means surrounding the body to form an air chamber between it and the body, a plurality of furnace pipes leading from the air chamber, partitions dividing the upper portion of the air chamber into a plurality of compartments, one for each furnace pipe and a grate located horizontally in the lower half of the body.
3. In a furnace, a hollow body having open ends, front and rear closures for the body, horizontal flanges extending inwardly from the sides of the body, a curved baffle resting at its lower edges on the flanges and connected to the front closure, said baffle being located a distance below the top of the body, a back to the baffle positioned a distance in front of the rear body closure, means surrounding the body to form an air chamber between it and the body, a plurality of furnace pipes leading from the air chamber, and partitions dividing the upper part of the air chamber into a plurality of compartments, one for each furnace pipe.
4. In a furnace, a hollow body open at both ends and having flanges extending outwardly at each end, a front and back to the body and detachably connected to said flanges to close the body, inwardly extending horizontal flanges formed at each side 55 of the body, a baffle located below the top of the body and resting on the last named flanges and detachably connected at its front to the front of the body, a back to the baffle located a distance in front of the back of the body, a grate positioned and supported horizontally in the lower front portion of the body, and means to obtain entrance into the body through the front both above and below the grate.
5. In a furnace, a hollow body having horizontal flanges projecting both inwardly and outwardly from the sides thereof, a front and a back detachably connected at the ends of the body to close it, a baffle located in the upper portion of the body and resting on the inwardly extending flanges and spaced a distance from the top of the body, a back to the baffle positioned a distance in front of the back of the body, a grate located horizontally in the lower part of the body, means inclosing the body to form an air chamber between it and the body, and partitions dividing the air chamber into compartments, the lower edges of said partitions resting on the upper portion of the body and the outwardly extending flanges thereof.
6. In a furnace, a hollow body comprised of upper and lower halves each having outwardly extending horizontal flanges at its edges, means connecting the flanges together, inwardly extending horizontal flanges formed on the inner sides of one of said halves, a baffle resting at its side edges on said inwardly extending flanges, and spaced a distance below the upper half of the body, a vertical back to said baffle located a distance in front of the rear of said body, front and back closures for the body, a grate located horizontally in the lower portion of the body, a baffle wall pivotally mounted at the rear end of and located above the grate, said baffle wall being located adjacent the said vertical back, and means to adjust and hold the baffle wall in a plurality of positions with respect to said vertical back.
7. In a furnace, a hollow body having horizontal flanges projecting inwardly from opposed sides thereof, a front and back detachably connected at the ends of the body, a baffle located in the upper portion of the body and resting at its side edges on the inwardly extending flanges and spaced a distance below the top of the body, said baffle being adapted to be slidably inserted into the body on the said flanges, means connecting the baffle to the said front, a back to the baffle positioned a distance in front of the back of the body, and a grate located horizontally in the lower part of the body.

In testimony whereof I affix my signature in presence of two witnesses.
